DENTAL DEVICE

George M. Hollenback, Los Angeles, Calif.

Application March 1, 1938, Serial No. 193,318

3 Claims. (Cl. 83—10)

This invention broadly relates to a dental device, and particularly to means adapted to triturate amalgams.

It is common practice by dentists to use in the cavities of teeth amalgams of various metals, particularly where the tooth is not readily observable and an inexpensive filling is desired by the patient. However, amalgams have not proved entirely satisfactory due to various causes, among which may be specifically mentioned, that of contraction. The average amalgam, so-called, consists of mercury and alloy. The alloy varies with different manufacturers, based upon their experience, but generally contains copper, silver, and possibly zinc. It has been found that particle size of the filings of the metal alloy may control contraction of the amalgam when the amalgam is triturated. In fact, the subject of expansion and contraction of amalgams has been studied over a period of time. It is possible to cause considerable contraction of the amalgam when the amalgam is not properly triturated.

Trituration of an alloy with mercury is usually accomplished in what is termed a mortar through the medium of a pestle. This pestle is revolved within the mortar to effect trituration but unless a given pressure is maintained by the pestle upon the amalgam, varying degrees of contraction may result in the amalgam, irrespective of the given rate of speed at which the pestle is moved over the amalgam. It is ordinary practice for a dentist to place a drop or more of triple distilled mercury over the alloy and to work the mercury and alloy together, to wit, triturate it. After the dentist has reached what to him or experience teaches is proper trituration, the amalgam is removed from the mortar, usually by rolling the same into a compact form by the fingers whereupon, in the palm of the hand, the amalgam is mulled. This is done in order to remove excess mercury and to assure a proper coating of all of the alloy grains with mercury. Usually, the mulled amalgam is rolled into a cylindrical form and cut into small pieces so that a short cylinder may be placed in the tooth cavity and thereafter condensed by a suitable condenser.

Over a period of time, the inventor has made tests for dimensional changes, flow and crushing strength of various amalgams, and has found that the factors just mentioned can be controlled to a high degree by the invention to be described. In fact, it is possible for the tyro dentist to obtain results comparable to those obtained by the most expert dental technician.

Under-trituration will tend to increase expansion and to reduce crushing strength of an amalgam and to increase flow. Over-trituration will tend to produce shrinkage in the amalgam in direct proportion to the amount of over-trituration, to increase the crushing strength and flow. 5 Correct trituration will prevent shrinkage and tend to hold expansion within desirable limits. It will decrease flow and increase crushing strength.

While I have mentioned mulling of the amalgam in the hand, still I do not recommend this 10 procedure, but prefer to place the amalgam after its removal from the mortar in a small piece of rubber dam and work the amalgam in said dam into a compact mass. The reason for this is that any method of manipulation which tends to contaminate the amalgam in any way may result in an inferior amalgam.

An object of the present invention is the provision of means whereby correct trituration of an amalgam may be obtained.

Another object is the provision of means whereby an amalgam may be formed in such a manner that the result to be obtained from said amalgam in use or service may be accurately predetermined.

Another object is the provision of a device for 25 use in triturating amalgams which may be used as readily by an amateur as a professional, the same results being obtained in the amalgam.

Another object is the provision of a device of the character stated, wherein accurate pressure 30 engagement may be maintained on an amalgam during trituration thereof.

Another object is the provision of a pestle and mortar wherein the pestle may be maintained at a selected pressure engagement with the said 35 mortar at all times during rotation of the said pestle.

Another object is the provision of suitable means for use in conjunction with a pestle and a mortar adapted to receive said pestle whereby 40 a technician is effectively prevented from increasing pressure of said pestle against said mortar during movement thereof.

Other objects of the invention consist of a device which is inexpensive in cost of manufacture, efficient in operation, capable of performing superior results for the purpose intended, is compact and ornamental in appearance, capable of being readily cleaned, easily assembled, and of great utility.

With the above mentioned and other objects in view, the invention consists in the novel and useful provision, formation, construction, association, and relative arrangement of parts, members and features, all as depicted in a certain embed- 50 55

ment in the accompanying drawing, described generally, and more particularly pointed out in the claims.

In the drawing:

5 Figure 1 is a perspective view of my dental device as an entirety, and,

Figure 2 is a vertical sectional view on the line 2—2 of Figure 1.

10 Referring now with particularity to the drawing, I provide a base 1 which may be substantially circular in form and provided with an eccentric concavity 2 in the upper surface of said base. This concavity is adapted to have received therein and to hold in position a mortar 3. What 15 is termed a mortar usually comprises a bowl-like receptacle and, in the present instance, the bowl portion is provided on the inner surface of the base with a raised center 4. This construction results in the provision of an annular concavity 20 5. Adapted for reception within the bowl portion of the mortar and particularly in the concavity 5, is a pestle 6. A tubular shank 7, provided with a cap 8, has the cap thereof secured to the pestle at its upper end in any ordinary 25 manner. The end opposite the cap 8 carries a socket member 9, the socket portion being at 10. Adapted for reception in the socket is a ball head 11 on one end of a shank 12.

The base 1 has secured thereto a pedestal 13, such as by having a reduced threaded diameter portion threaded into an opening of the base, as indicated at 14 and an arm 15 secured at the opposite end of the pedestal 13. The arm is provided with a transverse bore adapted to receive 30 a bushing 16. Through the bushing is passed the shank 12.

35 Adapted to be carried by the shank 12 is an annular disc 17, provided with an annular enlargement 18 upon the under surface thereof, which annular enlargement is pinned at 19, or otherwise secured to the shank 12. The disc 17 is adapted to sustain and act as a platform for one or more annular weights, such as shown at 20, 21 and 22. Thus, a constant pressure is 40 exerted by said weights in a downward direction to impose a given pressure between the head of the pestle and the concavity 5 of the mortar. Surrounding the shank 7 is a double conical spring 23. One end of said spring may be secured to the cap 8, the other end being free. This spring acts as the handle or finger-hold for 45 actuating the pestle. By separating the coils of the spring as designated in the drawing, any attempted downward pressure is immediately absorbed by the spring without in any manner increasing the pressure of the pestle against the 50 mortar.

55 General directions for actuating mortars and as accepted by dentists everywhere, is to hold the pestle with a pin grip, and this practice 60 should be followed so far as actuation of the pestle is concerned. In other words, the finger-hold or handle portion 23 should be held with a pin grip between the thumb and the first finger.

65 The operation, uses and advantages of the invention are as follows:

Having a good alloy with known characteristics as furnished by the manufacturer thereof, and assuming the use of triple distilled mercury and combining the same in the proper proportions 70 as indicated by the manufacturer of the alloy, by way of example, this proportion being as 5 to 8, the same is placed within the mortar. The

pressure to be exerted by the pestle upon this material may be three pounds and, accordingly, a proper weight is supported upon the platform 5 17. It is known that the number of revolutions of the pestle within the mortar greatly affects the characteristics of the amalgam so far as increase or decrease of flow, and expansion or shrinkage are concerned. Consequently, all the manipulator needs to do with the present invention is to know the correct pressure that should 10 be exerted at all times on the amalgam, and then to count the revolutions of the pestle in the mortar. These revolutions may be made rapidly or slowly, as desired. If we assume 150 revolutions with a given pressure, we are assured that 15 the same character of amalgam will always produce a like result in the finished product. The pestle is easily revolved due to the ball and socket arrangement and the weight or weights on the platform exert a constant downward pressure 20 under gravity influence. It will be observed that the ball 11 is adapted to be directly centered over the raised center of the mortar.

The device works exceedingly easily and produces efficient results, as it readily may be seen 25 that lateral and vertical pressures other than that exerted downwardly by the weights is effectively overcome by the construction described and shown.

It is obvious that various changes and modifications and variations may be made in practicing the invention in departure from the particular showing of the drawing and description as given without, however, departing from the true 30 spirit of the invention.

I claim:

1. In a dental device of the character disclosed; a mortar formed with a raised center defining an annular pathway; a pestle disposed in said pathway and guided thereby when moved 40 therein, weight means, and means slidably guiding the weight means along a vertical axis passing through the axis of the raised center of the mortar, and swivel means between the second named means and the pestle, whereby the weight means exerts a constant downward pressure on 45 said pestle.

2. In a dental device of the character disclosed; a mortar formed with a raised center defining an annular pathway, a pestle disposed in said pathway and guided thereby when moved 50 therein, weight means, and means slidably guiding the weight means along a vertical axis passing through the axis of the raised center of the mortar, and means between the second named means and the pestle whereby the said weight means exerts a constant downward pressure on said pestle, and a spring "finger hold" on said 55 pestle through which the pestle may be moved in said pathway.

3. In a dental device of the character disclosed; a mortar formed with a raised center defining an annular pathway, a pestle disposed in said pathway and guided thereby when moved 60 therein, weight means, and means slidably guiding the weight means along a vertical axis passing through the axis of the raised center of the mortar, means transmitting the weight against the pestle shank while permitting gyratory motion of said shank, and a conical spring on said 65 shank adapted to be held by the fingers of the operator to move the pestle.

GEORGE M. HOLLENBACK.
